US00D685956S

(12) **United States Design Patent**
Zhu et al.

(10) **Patent No.:** **US D685,956 S**
(45) **Date of Patent:** **** Jul. 9, 2013**

(54) **MINI RETRCTOR**

(75) Inventors: **Haiyuan Zhu**, Suzhou (CN); **Xinggen Huang**, Suzhou (CN)

(73) Assignee: **Suzhou Petmate Industry & Trade Co., Ltd.**, Suzhou (CN)

(**) Term: **14 Years**

(21) Appl. No.: **29/407,820**

(22) Filed: **Dec. 2, 2011**

(30) **Foreign Application Priority Data**

Jun. 2, 2011 (CN) 2011 3 0155551

(51) **LOC (9) Cl.** **30-04**

(52) **U.S. Cl.**

USPC **D30/153**

(57) **CLAIM**

The ornamental design for a mini retractor, as shown and described.

DESCRIPTION

FIG. 1 is a top, front, right-side perspective view of a mini retractor;

FIG. 2 is a front view thereof;

FIG. 3 is a top view thereof;

FIG. 4 is a right-side view thereof;

FIG. 5 is a left-side view thereof;

FIG. 6 is a rear view thereof;

FIG. 7 is a bottom view thereof;

FIG. 8 is a top, rear, left-side perspective view thereof; and, FIG. 9 is another top, rear, left-side perspective view thereof that illustrates an unclaimed strap portion protruding therefrom.

Broken lines and unshaded portions contained within broken line are not claimed.

1 Claim, 8 Drawing Sheets
